(57) CLAIM

The ornamental design for a combined showerhead and tankless water heater, as shown and described.

DESCRIPTION

FIG. 1 is a bottom perspective view showing a first embodiment of the new design;

FIG. 2 is a top perspective view thereof;

FIG. 3 is a bottom view thereof;

FIG. 4 is a top view thereof;

FIG. 5 is a right side view thereof;

FIG. 6 is a left side view thereof;

FIG. 7 is a front view thereof;

FIG. 8 is a back view thereof;

FIG. 9 is a bottom perspective view showing a second embodiment of the new design;

FIG. 10 is a bottom view thereof; and,

FIG. 11 is a front view thereof.

The remaining views for the second embodiment of the new design are the same as the corresponding views for the first embodiment of the new design.

The broken line representations shown in the drawings are for illustrative purposes only and form no part of the claimed design.
